United States Patent Office

Des. 177,179
Patented Mar. 20, 1956

177,179

PORTABLE DISPENSER

Clare E. Hodgman, Mamaroneck, N. Y., assignor to The Coca-Cola Company, New York, N. Y., a corporation of Delaware

Application February 21, 1955, Serial No. 34,593

Term of patent 14 years

(Cl. D14—3)

FIG. 3.

Fig. 1 is a view in perspective of a portable dispenser embodying my new design;

Fig. 2 is a side view; and

Fig. 3 is a top view of said device.

The rear of the cart is plain, and the side opposite Fig. 2 is like the one shown.

I claim:

The ornamental design for a portable dispenser, as shown and described.
